UNITED STATES PATENT OFFICE.

MARTIN F. SLATTERY, OF COHOES, AND CHARLES A. LINEHAN, OF SCHENECTADY,
NEW YORK.

AUTOMATIC TRAIN-STOP.

1,150,788.

Specification of Letters Patent.

Patented Aug. 17, 1915.

Application filed July 21, 1914. Serial No. 852,265.

To all whom it may concern:

Be it known that we, MARTIN F. SLATTERY and CHARLES A. LINEHAN, citizens of the United States, residing at Cohoes and 5 Schenectady, respectively, in the counties of Albany and Schenectady, respectively, and State of New York, have invented new and useful Improvements in Automatic Train- Stops, of which the following is a specification.

This invention relates to improvements in train stopping devices and has particular application to a device for use in conjunction with the road signaling system.

15 In carrying out the present invention, it is our purpose to provide a device of the class described which may be quickly and conveniently installed and connected with the road signal system now in use without necessitating elaborate changes in the signal system.

It is also our purpose to provide a device of the type set forth which will embrace the desired features of simplicity, efficiency and 25 durability, which may be installed and maintained at a minimum expense and which will operate effectively under all conditions.

With the above and other objects in view, 30 the invention consists in the construction, combination and arrangement of parts hereinafter set forth in and falling within the scope of the claim.

In the accompanying drawings; Figure 1 35 is a cross sectional view through a trackway showing the track obstacle and the connection between the latter and adjacent road signal. Fig. 2 is a view in side elevation of the track obstacle removed from the track- way. Fig. 3 is a cross sectional view there- 40 through. Fig. 4 is a diagrammatic plan view showing the relative positions of the car carried mechanism and track obstacle.

Referring now to the drawings in detail, 45 1 designates a trackway which, in the present instance, is divided into blocks and located adjacent to the entrance to each block and controlling traffic into the same is a semaphore 2 comprising the usual standard 50 3 and signal blade 4 pivoted upon the standard adjacent to the upper end thereof and operating rod 5, the latter having the upper end thereof connected with the signal blade and the lower extremity connected 55 with the operating motor of the semaphore

so that the blade may be swung to danger and clear positions.

Our improved train stopping apparatus is designed for use in conjunction with the block signaling system and is so constructed 60 that the same may be installed and connected up with the road signals or semaphores without necessitating elaborate changes in the construction of the semaphores. This train stopping apparatus embodies an obstacle 6 located at the entrance to each block and disposed between the lines of rails of the trackway approximately centrally thereof, such obstacle comprising a base plate 7 bolted or otherwise fastened to the upper surface of the ties and extending transversely of the trackway, standards 8, 8 65 uprising from the base plate and spaced apart in parallelism and carrying, adjacent to the upper extremities thereof, a pivot pin 9, and an arm 10 mounted upon the pin 9 and capable of swinging movement transversely of the trackway and adapted to lie in a horizontal plane and a vertical plane, the upper end of the arm 10, when the latter 70 is vertical, projecting above the upper extremity of the standards 8, 8. Arranged adjacent to the semaphore standard 3 is a base plate 11 and uprising from the base plate 11 is a supporting standard 12 and pivoted to one face of the supporting standard 12 is a bell crank lever 13 having a horizontal limb and a depending vertical limb. Pivotedly connected to the lower extremity of the depending vertical limb of the bell crank lever 13 is one end of a horizontal rod 14 having the opposite end pivotally connected with the lower extremity of the arm 10, such 75 rod 14 lying beneath the adjacent line of rails. In the present instance, the base 7 is slotted to accommodate the lower end of the arm 10 and depending from the base is a U-shaped yoke 6' having the upper extremities of the limbs thereof secured to the base 80 at the opposite sides of the slot therein, such yoke incasing the connection between the adjacent end of the arm 10 and the rod 14. Projecting outwardly from the actuating rod 5 of the signal blade in a plane coincident with that of the horizontal limb of the bell crank lever is a pin 15 and pivotally connected with the pin 15 is one end of a link 16 having the opposite end thereof pivoted to the horizontal limb of the bell crank 85 lever as at 17.

In practice, when the signal blade is in clear position the link 16 and bell crank lever 13 are actuated to push the rod 14 and so swing the arm 10 out of vertical position and into inactive position, while when the blade is actuated to danger position the upward movement of the rod 5 actuates the link 16 and bell crank lever 13 with the effect to pull the rod 14 and so swing the arm 10 to active position. It will be noted that the axis of the arm 10 is arranged parallel with the trackway, while the arm swings in a plane transversely of the trackway so that when the controlling element of the car carried mechanism impacts against one side or the other of the arm 10 the latter will remain immovable and the connections between the arm and signal blade relieved of any strain.

In the embodiment of our invention selected for illustrative purposes, the car carried stopping mechanism comprises a valve 18 connected in the train line air pipe and provided with a depending handle adapted to contact with the arm 10 when the latter is in vertical or active position so that the valve will be opened and the pressure in the brake pipe reduced to effect an application of the brakes to the wheels. In the present instance, the central portion of the pilot of the locomotive is formed with a longitudinal slot to accommodate the obstacle.

From the foregoing description taken in connection with the accompanying drawings, the construction, mode of operation and manner of employing our invention will be readily apparent.

Copies of this patent may be obtained for five cents each, by addressing the "Commissioner of Patents, Washington, D. C."

It will be seen that we have provided an automatic train stop wherein the track obstacle may be readily and quickly connected up with the road signal system without changing the structure of the latter and wherein the connections between the obstacle and the signal will be relieved of any strain or stress due to the impact between the handle of the valve in the brake pipe and the arm of the obstacle.

We claim:

A track obstacle comprising a base plate, standards uprising from said base plate and spaced apart in parallelism, a pivot pin carried by said standards adjacent to the upper extremities thereof and extending longitudinally of the trackway, an arm pivoted between said standards and capable of swinging movement to active and inactive positions and movable transversely of the trackway, said base being slotted to accommodate the lower end of said arm, a rod connected with the lower extremity of said arm, means for actuating said rod to swing said arm, and a U-shaped yoke having the ends of the limbs thereof secured to the under surface of said base at the opposite sides of the slot therein and surrounding the connection between said rod and arm.

In testimony whereof we affix our signatures in presence of two witnesses.

MARTIN F. SLATTERY.
CHARLES A. LINEHAN.
